COMBINED MAGNETIC DOOR HOLDER AND STOP

Maxwell Ingram, 15 Hamilton Ave., Dumont, N.J.

Filed June 17, 1959, Ser. No. 56,400

Term of patent 14 years

(Cl. D10—7)

Fig. 1

Fig. 2

FIGURE 1 is a perspective view of a combined magnetic door holder and stop, showing my new design with the door holder and stop in disengaged position; and

FIGURE 2 is a side elevational view thereof showing the door holder and stop in engagement.

I claim:

The ornamental design for a combined magnetic door holder and stop, substantially as shown.
